MONEY BOX

Pedro A. González, Mayaguez, P. R.

Application July 12, 1944, Serial No. 544,600

1 Claim. (Cl. 232—4)

This invention relates to money boxes and more particularly to such boxes adapted to be used as banks or the like.

A primary object of this invention is the provision of a money box having a concealed lock whereby one unacquainted with the construction of the box encounters difficulty in locating the position of the opening of the box.

A further object is the provision of such a money box provided with a lid or cover adapted to be locked in position and a supplemental second lid exterior of the first lid concealing the locking means thereof.

A still further object of the invention is the provision of a money box having a plurality of sides or ends substantially identical in design, only one of which is removable to provide access to the locked interior cover of the box.

A still further object is the provision of a money box wherein the supplemental cover is disguised to conceal the fact that it is such a cover.

A more specific object is the provision in association with such a supplemental outer cover of means whereby one acquainted with the construction of the box may readily remove the same from association with the box by simple finger pressure.

Additional objects reside in the combinations of elements, features of construction, and arrangements of parts all as will be more fully pointed out hereinafter and disclosed in the accompanying drawings, wherein there is shown a preferred form of this inventive concept.

In the drawings:

Figure 1 is a perspective view of one form of money box embodying this invention showing the upper cover in position for removal therefrom.

Figure 2 is a view similar to Figure 1 but showing the outer cover removed.

Figure 3 is an end elevational view of the device of Figure 1, the position of certain parts thereof being indicated in dotted lines.

Figure 4 is a side sectional view of the construction disclosing certain interior mechanism.

Figure 5 is a sectional view taken substantially along the line 5—5 of Figure 4 as viewed from the bottom.

Figure 6 is a bottom plan view of the outer cover for the box, and

Figure 7 is an end elevational view of the cover shown in Figure 6.

Like reference numerals refer to like parts throughout the several views of the drawings.

Having reference now to the drawings, there is

generally indicated at 10 a money box or bank comprised of side walls 11 beveled along their edges as at 12 and fitted together to form a rectangular box, a bottom 13, and a top or cover 14 generally indicated at 14, sides 11 being secured together as by nails or screws 15 and base 13 being secured in position within the rectangle formed by sides 11 as by nails or screws 16. Cover 14 is adapted to seat on a ledge 17 interiorly disposed in box 10 and positioned substantially below the top of side walls 11. This ledge 17 is provided with two oppositely disposed apertures or recesses 18 and 19, respectively. A projecting member 20 secured to the underside of cover 14 as by nails or screws 21 and having an extending portion offset therefrom (see Figures 4 and 5), is adapted, when the cover is in position to engage recess 18. The bolt 22 of a lock, generally indicated at 23, having a flanged housing 24, is adapted to engage in recess 19, which serves as a keeper therefor. Flanged housing 24 is also secured to the underside of cover 14 as by suitable nails or screws 25, and provided with a keyhole 26 extending through cover 14 to the outer side thereof. Cover 14 is also provided with a slot 30 extending therethrough to permit the insertion of coins and the like into box 10. Secured to the underside of cover 14, as by nails or screws 31, are a plurality of spring fingers 32 adapted to cross beneath slot 30, whereby money, such as coins may be passed inwardly through the slot, but not outwardly therethrough.

It will be seen from a consideration of the drawings that when cover 14 is positioned on, and secured to ledge 17 by means of member 20 and lock bolt 22 a recess 33 of a substantial depth is left between the top surface thereof and the top of side walls 11. A supplemental or outer cover 35 of a thickness substantially equal to the depth of recess 33 is adapted to fit snugly therein in such manner that the outward appearance of cover 35 and base 13 are substantially identical. To enhance the deception short dummy nails 36 are hampered into the upper edges of sides 11 but not therethrough to present an identical appearance with nails 16 securing the base 13 to sides 11 of the box. The corners of outer cover 35 are, as best shown in Figures 6 and 7, tapered or beveled as at 37 whereby downward pressure on any corner will lift the opposite diagonal corner out of recess 33 in order that the same may be grasped or engaged by a suitable lifting instrument to remove the cover 35 from the recess to provide access to cover 14, either for the insertion of coins through slot 30 or removal of

cover 14 from box 10. Such removal is effected by the insertion of a key in keyhole 26 to withdraw bolt 22 from keeper 19. An upward pull on the key then raises the edge of cover 14 adjacent thereto out of engagement with ledge 17, it here being pointed out that the inner edges of cover 14 are beveled as at 38 (see Figure 4) and that such bevel permits member 20 to slide outwardly out of engagement with recess 18 whereupon cover 14 may be removed completely from box 10 and access had to the contents thereof.

It will now appear that the means of gaining access to the interior of the box is effectively concealed from one unacquainted with the construction and operation thereof, by the outer cover 35 which is, as previously pointed, identical in outward appearance with base 13. It will also appear that ready access may be had to the interior of the box by one knowing the mode of operation of the structure and possessing a key to lock 23.

While in the foregoing the device has been described as comprised of a plurality of sides of a material, such as wood, adapted for the passage of nails or screws therethrough, it will be understood, that the same may be made of metal, plastic, or other desired material, and that instead of being formed of four side walls secured in related assembly the side walls may be cast or molded as an integral box-like structure.

Now from the foregoing it will be seen that there is herein provided a money box or the like achieving all the objects of this invention and many others including advantages of practical utility and commercial importance.

As many embodiments may be made of this inventive concept and as many modifications may be made in the embodiment hereinbefore shown and described, it is to be understood that all matter herein is to be interpreted merely as illustrative and not in a limiting sense.

I claim:

In a device of the character described, a box, comprised of side walls and a base, an inner cover having an opening affording access to said box positioned between said side walls and spaced from the tops of said side walls to form a recess thereabove, and an outer cover of a thickness equal to the depth of said recess and identical in appearance to said base positioned in said recess, the top of said outer cover being flush with the tops of said side walls to conceal said first-mentioned cover, at least one corner of the under side of said outer cover being bevelled so that pressure on the outer side thereof will cause the outer cover to rock on the inner cover and lift an opposite corner whereby the outer cover may be removed.

PEDRO A. GONZÁLEZ.
